WINDOW CONSTRUCTION

John Conville, Antioch, Ill., assignor, by mesne assignments, to In-A-Wall Corporation, Cary, Ill., a corporation of Illinois

Filed Nov. 16, 1956, Ser. No. 622,627

2 Claims. (Cl. 160—101)

This invention relates to a window construction and more particularly to a window construction having built-in storm and screen protection.

An object of this invention is to provide a window construction in which storm and screen inserts are removably built into the structure and between a pair of sliding window members and the inserts are concealed from both inside and outside of the window.

Another object of the invention is to provide a double-hung window construction including upper and lower window sashes which are arranged with a space between their meeting rails so that a pair of vertically disposed inserts may be placed therebetween to provide the desired storm or screen protection depending upon the structure carried by the inserts.

A further object of the invention is to provide a window construction as defined in the preceding paragraph wherein the vertically disposed inserts are arranged in abutting relation in vertically disposed channels positioned between the upper and lower window sash with one of the sashes positioned to form part of said channels and being removable to enable placement and removal of the inserts in the channels.

A further object of the invention is to provide a window construction including a window sash which is removably mounted in the window framing by means which include a friction strip extending along one sash stile in sliding engagement with the adjacent window jamb, and means carried by the sash stile for moving the friction strip to a position to permit withdrawal of the window sash and to additionally vary the friction engagement between the friction strip and the jamb to provide proper counterbalance of the sash.

The objects of the invention generally set forth together with other ancillary advantages are attained by the construction and arrangement shown by way of illustration in the accompanying drawing, in which:

Fig. 1 is a vertical elevation of a window construction including the window framing, looking from the inside out, and with the lower sash slightly raised;

Fig. 2 is a horizontal section taken generally along the line 2—2 in Fig. 1;

Fig. 3 is a vertical section taken generally along the line 3—3 in Fig. 1 but with the lower sash closed;

Fig. 4 is a fragmentary view in elevation of a friction strip and the operating mechanism therefor on an enlarged scale;

Fig. 5 is a horizontal section taken generally along the line 5—5 in Fig. 4; and

Fig. 6 is a detailed view of an operating key for the friction strip adjusting mechanism.

While this invention is susceptible of embodiment in many different forms, there is shown in the drawings and will herein be described in detail an illustrative embodiment of the invention with the understanding that the present disclosure is to be considered as an exemplification of the principles of the invention and is not intended to limit the invention to the embodiment illus-

2

trated. The scope of the invention will be pointed out in the appended claims.

The window construction as shown in Figs. 1-3 comprises a lower window sash 1 and an upper window sash 2 having spaced apart meeting rails 3 and 4, respectively. The upper window sash 2 has stiles 5 and 6 at its sides. The stile 6 has vertically extending grooves 7 which slidably engage projections 8 formed in a block 9 forming part of one side jamb. The groove 7 and projections 8 constitute coacting means for slidably confining the sash stile 6. The sash stile 5 carries a vertically extending friction strip 10 which is generally U shaped and has one leg 11 embedded in the stile 5 as by providing a vertically extending sawcut therein. The friction strip is arranged to be somewhat flexible and may be made of aluminum or other suitable material. A base part 12 of the friction strip 10 is arranged to slidably engage a guide surface 13 formed in a block 14 forming part of the side jamb. The guide surface 13 tapers inwardly away from the sash stile 5. The base part 12 of the friction strip and the block 14 have slidably interengaged parts, as indicated at 15, to define coacting means for slidably confining the sash stile 5. Another leg 15a of the friction strip extends vertically along the front of the sash stile 5 for a purpose more fully set forth hereinafter.

The lower window sash 1 has stiles 16 and 17 at the side thereof, and the stile 17 is slidably confined to a vertically extending side jamb section 18 by coacting means, indicated at 19, comprising interengaging grooves in the stile 17 and projections on the jamb section 18. The stile 16 carries a friction strip 20 generally similar to that carried by the upper window sash 2 and has a leg 21 embedded in the stile 16 and a base part 22 at an oblique angle to the leg 21 which slidably engages a surface 23 formed in the side jamb member 24 and which tapers inwardly away from the sash stile 16. Another leg 23 of the friction strip 20 extends vertically along the front of the stile 16, and the connection thereof to the base part 22 of the friction strip forms, with a notch 26 in the side jamb member 23, coacting means for slidably confining the stile 16.

As shown in Fig. 3, the meeting rails 3 and 4 are spaced apart to provide a space through which a pair of vertically displaced inserts 27 and 28 may extend in abutting relation. These inserts may comprise a surround frame formed of a U-shaped, metal channel and receive panels of glass, such as indicated at 29, or a section of screen, such as indicated at 30, each of which may be secured to the surround frame by being embedded in suitable material.

The right-hand sides of these inserts 27 and 28, looking at Fig. 2, are confined in a channel extending vertically between the upper and lower window sashes. This channel is defined by the jamb sections 18 and 9 and a base jamb section 31 to which the jamb sections 9 and 18 are secured, the jamb sections 9, 18 and 31 forming a side jamb.

The left-hand sides of the inserts 27 and 28, looking at Fig. 2, are confined in the space between the upper and lower window sashes at one of their faces by the jamb sections 14 and 24 which comprise a side jamb and forming in part a channel which is completed by the stile 16 of the lower window sash 1.

As in conventional window construction, there may be a sill 32 from which the side jambs extend upwardly, and exterior trim members 33 and 34 also extend upwardly from the sill and partially over blind stop members 35 and 36 which engage and partially enclose the outer weather faces of the upper window sash stiles 5 and 6. The other structure surrounding the window construction may include a conventional wall construction.

It will be seen from the foregoing that a pair of slideable window members have been provided with a space between their meeting rails so that a pair of vertically disposed inserts may be disposed therebetween in abutting relation with each other, and the inserts are confined by a window sash and cooperating side jamb structure.

In order to remove the lower window sash 1 so as to give access to the inserts 27 and 28 for removal thereof or to permit insertion of the inserts, the mechanism as shown particularly in Figs. 4 and 5 is provided. The friction strip 20 is provided with a pair of vertically spaced, elliptical openings 40 and 41, as shown in Fig. 1. Associated with each of these openings is a rotatable plug 42 rotatably embedded in an opening in the stile 16. This plug has an exposed flange 43 which is circular so that portions thereof lie behind the friction strip 25 in order to confine the plug in the stile. Extending outwardly from the flange 43 is a T-shaped projection 44 including a pair of legs 45 and 46 of equal length and a cam section 47 having a slightly greater length than either of the legs 45 or 46. With this construction, rotation of the plug 42 in a clockwise direction, looking at Fig. 4, will carry the cam section 47 in a clockwise direction so as to ride against the edge of the non-circular opening 40 and function to pull the friction strip 20 away from the jamb surface 23 and clear of the notch 26 formed in the side jamb so that the edge of the window including sash stile 16 may be moved inwardly a distance sufficient to then permit release of the coacting confining means associated with the stile 17. The cam section 47 may be moved back generally to the position shown in Fig. 4 after the window sash is again put in place so as to return the friction strip 20 into sliding engagement with the jamb surface 23 and behind the jamb notch 26. The rotatable plug 42 may also be slightly adjusted in either direction of rotation so as to vary the friction engagement of the friction strip 20 with the surface 23 in order to properly counterbalance the sash.

A suitable key for operating the plug 42 is shown in Fig. 6 wherein a disc 48 has a handle 49 secured thereto, and the disc 48 carries four raised lugs 50 which may be placed against and interfitted with the raised, T-shaped projection 44 in order to facilitate turning of the lug.

The structure shown in Figs. 4 and 5 is also utilized with the friction strip 10 associated with the upper window sash 5 to enable removal of the upper sash, and the openings in the friction strip 10 are shown at 51 and 52 in the upper sash 2.

The structure for rendering the sashes removable, as well as adjusting the sliding action thereof with a minimum of force, renders it extremely simple for a person to remove or replace a window sash for purposes of cleaning the window glass or handling inserts 27 and 28.

It will be obvious that either screen or storm glass may be carried by the inserts 27 and 28, depending upon the season of the year, and it is possible to always

have one insert provided with glass, as shown at 29, and to have two different, alternatively usable inserts at 27, one of which may have screen material, and the other glass.

5 I claim:

1. In a window construction having window framing including jambs, a lintel and a sill, upper and lower window sashes having upper and lower rails and stiles with the lower rail of the upper sash and the upper rail 10 of the lower sash spaced from each other when the sashes are closed, means on the jambs forming guides for the upper and lower window sashes, and a pair of vertically displaced inserts extending through the space between the meeting rails and adapted to carry 15 structure for providing either storm or screen protection, one of said jambs having a vertically extending channel of generally U-shaped transverse section between the upper and lower window sashes in which one edge of the inserts is placed, said other jamb having a vertically extending section with a generally L-shaped transverse section and coacting with the lower window sash to form an insert confining channel at the other edge of the inserts, the other edge of the inserts forming a parting stop.
2. In a double hung window construction, upper and lower sliding window members, each window member having upper and lower rails and stiles with glass therein, guide means in which said window members are 20 slidable and positioned to maintain the window members in offset parallel planes at a distance from each other to provide a space therebetween, and a pair of storm panel inserts having surround frames disposed in a common vertical plane in said space and at least coextensive in area with an area defined by the window members when closed with an upper insert resting on the 25 lower insert, said upper and lower inserts being spaced from the upper and lower window members respectively substantially the same distance to provide air spaces with optimum insulating properties, the surround frames of 30 the pair of inserts abutting each other at the level of the upper window member lower rail and the lower window member upper rail when the window members are closed and having a width substantially equal to said space to close off said space.
